**SILICON CONTROLLED RECTIFIER LOCK-UP
PROOF FLIP-FLOP**

Lowell D. Yates, El Paso, Tex., assignor to the United States of America as represented by the Secretary of the Army

Filed Feb. 9, 1965, Ser. No. 431,482
3 Claims. (Cl. 307—252)

The invention described herein may be manufactured and used by or for the Government for government purposes, without the payment to me of any royalty thereon.

The invention relates to silicon controlled rectifier capacitor turn-off circuits and more particularly to such a circuit which will not lock-up or fail when the time interval between the turn-on pulse and the turn-off pulse becomes too short to store enough energy in the commutating capacitor to provide the related silicon controlled rectifier with a reverse voltage whereby the related silicon controlled rectifier will be placed in the off condition.

Prior art silicon controlled rectifier capacitor turn-off circuits have a common limitation, that is, such circuits will lock or fail when the time interval between the turn-on pulse and the turn-off pulse becomes too short to store enough energy in the commutating capacitor to extinguish the related silicon controlled rectifier. Therefore, these prior art silicon controlled rectifier circuits cannot be effectively used in control circuits which require that the turn-off pulse time be a function of the error in a feedback loop without supplementary logic to insure against minimum time displacement between the turn-on and the turn-off signals.

An object of the invention is a new and novel solid state control means employing silicon controlled rectifiers in combination with commutation means for precise control of electronic or electromechanical devices.

Another object of the invention is a unique tristable silicon controlled rectifier switch provided with alternate turn-off pulses and which reverts temporarily to bistable operation as coincidence is approached.

Another object of the invention is an improved silicon controlled rectifier flip-flop circuit which will not lock-up or fail with a widely variable load or with a widely varying time displacement between turn-on and turn-off signals.

The specific nature of the invention as well as other objects and advantages thereof will clearly appear from the following description and accompanying drawings in which:

FIGURE 1 is a schematic diagram of the lock-up proof silicon controlled rectifier flip-flop of the invention; and

FIGURE 2 is a block diagram illustrating a simplified application of the lock-up proof silicon controlled rectifier flip-flop in a motor velocity control system.

FIGURE 1 shows the circuit 10 of the tristable silicon controlled rectifier lock-up proof flip-flop of the invention wherein silicon controlled rectifiers SCR₂ and SCR₃ are the turn-off means which are pulse fired alternately, each in turn shorting capacitor C₁ or C₃ across silicon controlled rectifier SCR₁ and turning it off. The anode of SCR₃ is connected through resistor R₂ to the D-C power supply 12 which is returned to common circuit 11. The anode of SCR₂ is similarly connected to D-C power supply 12 through resistor R₁ and the anode of SCR₁ is connected to D-C power supply 12 through the device to be controlled as represented by resistor R_L which may be an electric motor, or any electronic device. Commutation means of the flip-flop of the invention comprises capacitor C₁ which couples the anodes of SCR₂ and SCR₁, capacitor C₂ which couples the anodes of SCR₂ and SCR₃, and capacitor C₃ which couples the anodes of SCR₁ and SCR₃. The turn-on pulses applied to the gate of SCR₁

may be derived from a pulse timing generator as indicated by reference numeral 13. The even numbered turn-off pulses and the odd numbered turn-off pulses applied to the gates of SCR₃ and SCR₂, respectively, may be derived, for example, by means of a bistable multivibrator as indicated by reference numeral 14.

FIGURE 2 illustrates a simplified application of the invention wherein R_L is a motor having its shaft 15 coupled to a digital tachometer 16 which produces the turn-off signals, digital pulses, which are coupled to a bistable multivibrator 14. The multivibrator divides the digital pulses producing the odd and even pulses applied to the gates of SCR₂ and SCR₃. The timing generator 13 produces the turn-on pulses which are applied to the gate of SCR₁.

In operation of the lock-up proof silicon controlled rectifier flip-flop, normally functioning in a tristable state, a first turn-on pulse is applied to the gate of SCR₁ causing power from D-C power supply 12 to be applied to the load R_L and plate *a* of capacitor C₃ and plate *c* of capacitor C₁ to be shorted to near ground potential. The grounded plates *a* and *c* cause the capacitors C₃ and C₁ to charge to the potential of the D-C power supply 12, the grounded sides of capacitors C₃ and C₁ becoming negative. The first, odd numbered, turn-off pulse is then applied to the gate of SCR₂ whereby SCR₂ fires and capacitor C₁ is shorted across SCR₁. Since plate *c* of capacitor C₁ is now of negative polarity, this capacitor places a charge of reverse polarity across SCR₁ whereupon SCR₁ is extinguished and power for the load R_L is cut off. At this point SCR₁ and SCR₃ are in a nonconducting state and SCR₂ shorts plate *d* and plate *f* of capacitors C₁ and C₂, respectively, to ground, the capacitors charging to the potential of the D-C power supply 12 and the grounded plates *d* and *f* assuming a negative polarity. Now a second turn-on pulse is applied to the gate of SCR₁ whereby SCR₁ fires and the positive side *c* of capacitor C₁ is shorted to ground, placing a charge of reverse polarity across SCR₂ and extinguishing it. Again plate *a* of capacitor C₃ and plate *c* of capacitor C₁ are placed at ground potential, negative, and capacitors C₁ and C₃ again charge to the potential of the D-C power supply 12. The even numbered turn-off pulse is now applied to the gate of SCR₃ causing SCR₃ to fire and capacitor C₃ to short across SCR₁ whereby SCR₁ is extinguished. Since SCR₃ is now in a conducting state, plates *e* and *b* of capacitors C₂ and C₃, respectively, are placed at ground, negative, potential and capacitors C₂ and C₃ charge to the potential of D-C power supply 12. A third turn-on pulse is now applied to the gate of SCR₁, firing SCR₁ and placing capacitor C₃ across SCR₃ whereby SCR₃ is extinguished.

The invention may be best understood by considering the following description of a complete cycle of operations involving a coincidence or near coincidence of a turn-on pulse and a turn-off pulse where the time interval between said pulses becomes too short to store enough energy in the commutating capacitor and which in prior art SCR flip-flops causes a lock-up. A turn-on pulse applied to the gate of SCR₁ causes SCR₁ to fire and power to be applied to the load R_L. Shortly thereafter or near coincidence, the first turn-off pulse is applied to the gate of SCR₂ causing SCR₂ to fire whereby capacitor C₁ is shorted across SCR₁. However, due to the short interval of time between these two pulses, C₁ has not sufficient time to store enough energy to extinguish SCR₁. Therefore SCR₁ and SCR₂ remain in a state of conduction or lock-up. At this point in time of the cycle SCR₂ grounds plate *f* of capacitor C₂ and SCR₁ grounds plate *a* of capacitor C₃ and then both capacitors charge to the potential of D-C power supply 12 with plates *a* and *f* assuming a negative polarity. The second turn-on pulse is now applied to the gate of SCR₁, but has no effect because SCR₁ is already in a

state of conduction. Following the second turn-on pulse, a second turn-off pulse is applied to the gate of SCR_3 whereupon SCR_3 fires causing capacitors C_2 and C_3 to short across SCR_2 and SCR_1 extinguishing these two rectifiers whereupon the D-C power supply is disconnected from the load R_L . Next the third turn-on pulse is applied to the gate of SCR_1 causing it to fire whereby power is applied to the load R_L . The circuit now reverts to tristable operation as described in the foregoing paragraph.

Although a specific embodiment of this invention has been illustrated and described, it will be understood that this is but illustrative and that various modifications may be made therein without departing from the spirit of this invention and the scope of the appended claims.

What is claimed is:

1. A tristable controlled rectifier lock-up proof flip-flop including turn-on pulse means and turn-off pulse means and which reverts temporarily to bistable operation when coincidence between a turn-on pulse and a turn-off pulse occurs comprising in combination, a D-C power supply, a first controlled rectifier, a second controlled rectifier, a third controlled rectifier, each of said controlled rectifiers provided with anode, cathode and gate elements, the anodes of said controlled rectifiers connected to the positive pole of said D-C power supply, the cathodes of said controlled rectifiers connected to the negative pole of said D-C power supply, first commutation means coupling the anodes of said first and second controlled rectifiers, second commutation means coupling the anodes of said second and third controlled rectifiers, third commutation means coupling the anodes of said first and third controlled rectifiers, said turn-on pulse means connected to the gate of said first controlled rectifier whereby signals are applied to said gate turning on said first controlled rectifier, said turn-off pulse means generating alternate pulses and having one of its terminals connected to the gate of said second controlled rectifier and the other of its terminals connected to the gate of said third controlled rectifier causing said second and third controlled rectifiers to alternately fire whereby said first controlled rectifier is accordingly extinguished.

2. The invention in accordance with claim 1 wherein an electrically responsive load is connected in series with the anode of said first controlled rectifier and said D-C power supply.

3. A tristable controlled rectifier lock-up flip-flop which reverts temporarily to bistable operation when coincidence between a turn-on pulse and a turn-off pulse occurs comprising in combination, a D-C power supply, a first controlled rectifier, a second controlled rectifier, a third controlled rectifier, each of said controlled rectifiers provided with anode, cathode and gate elements, an electrically responsive load in series with the anode of said first controlled rectifier and the positive pole of the D-C power supply, a resistor in series with each of the anodes of the second and third controlled rectifiers and positive pole of the D-C power supply, the cathodes of said controlled rectifiers connected to the negative pole of the D-C power supply, a first commutating capacitor coupling the anodes of the first and second controlled rectifiers, a second commutating capacitor coupling the anodes of the second and third controlled rectifiers, a third commutating capacitor coupling the anodes of the first and third controlled rectifiers, pulse generating means adapted to apply firing signals to the gate of said first controlled rectifier whereby said first controlled rectifier is caused to conduct and power is applied to said electrically responsive load, a second pulse generating means adapted to alternately apply firing signals to gates of said second and third controlled rectifiers driving these rectifiers into conduction which alternately extinguish said first controlled rectifier whereby power to said electrical responsive means is connected and disconnected, said third controlled rectifier operating in a response to a firing pulse applied to its gate to short the second and third commutating capacitors across and extinguishing said first and second controlled rectifiers when the interval of time between the firing signal applied to said first controlled rectifier and the firing signal applied to said second controlled rectifier is too short to charge said first commutating capacitor to an extinguishing voltage for said first controlled rectifier.
